UNITED STATES PATENT OFFICE.

GEORGE W. HORTON, OF QUEENS, NEW YORK, ASSIGNOR TO JOHN W. BUNKER, OF NEW YORK, N. Y.

DESIGN FOR A GAME BOARD OR SIMILAR ARTICLE.

Application filed July 11, 1925. Serial No. 14,059. Term of patent 7 years.

To all whom it may concern:

Be it known that I, GEORGE W. HORTON, a citizen of the United States of America, residing at Queens, county of Queens, State of New York, have invented a new, original, and ornamental Design for a Game Board or Similar Article, of which the following is a specification, reference being had to the accompanying drawing, forming part hereof, which illustrates a face view of a game board showing my new design.

I claim:

The ornamental design for a game board or similar article, as shown.

Signed at New York city, New York, this 29th day of June, 1925.

GEORGE W. HORTON.
